MACHINE FOR COATING WAFERS

John R. Brandt, Chicago, Ill., assignor to Salerno Machinery Company, Chicago, Ill., a corporation of Illinois

Application September 2, 1948, Serial No. 47,463

6 Claims. (Cl. 107—27)

1

This invention relates to a machine for coating wafers or flat cakes, and more particularly to a novel hopper control mechanism and a novel form of hopper adapted to slide over stencil openings for application of a confectionery coating to a wafer or cake. This invention is an improvement over the type of machine disclosed in Patent No. 1,570,405 granted January 19, 1926, to Ferdinando G. Salerno, and the general operation of the machine to which this invention has been applied is generally similar thereto in its overall construction and general mode of operation. The machine is in the general class adapted for large scale production of sandwich cookies or cakes, the confection material such as chocolate or sugar icing being interposed between the top and bottom wafers.

The slideable coating hopper disclosed in said Salerno patent and also utilized in other similar machines, was adapted to be filled with a confection material which was fed from the bottom thereof and forced through stencil openings in a stencil box onto the upper surfaces of a plurality of wafers. The bottom of the hopper was open at all times and was provided with relatively broad, flat bearing surfaces which slidably engaged the upper surface of the stencil plate for reciprocal movement thereover. The plane of the bottom bearing surfaces of the hopper remained parallel with the upper surface of the stencil plate at all times during reciprocation.

While this construction was relatively satisfactory in general operation, it nevertheless required constant attention in that after a relatively few reciprocations over the stencil plate, a quantity of the coating material became smeared in a thick layer over the stencil plate and piled up at either end of the stencil box at the end of the hopper strokes. This caused the hopper to be raised off the stencil plate so that the coating was not cleanly applied to the wafer and was considerably thicker than that desired and determined by the thickness of the stencil plate. Moreover, the coating material, which was of relatively thick, plastic consistency, as it increased in quantity and thickness on the stencil plate, tended to retard machine operation, and often was forced over the upstanding marginal walls of the stencil box and spilled onto the machine parts, the conveyor belt and the wafers themselves.

As a result, it was necessary to shut down the entire machine at frequent intervals to clean off the surface of the stencil plate and the walls of the stencil box, which stoppage, multiplied by the

2

number of times required therefor during a working day, necessarily reduced to a considerable extent the daily machine output. Furthermore, an operator was required to maintain a constant vigil adjacent the hopper and stencil box so that the condition could be revealed before it was built up to an extreme, thus increasing labor costs and the ultimate cost of the finished product.

It is, therefore, an object of the present invention to overcome the above described disadvantages and difficulties encountered in the operation of prior coating machines.

Another object of the invention is to provide an improved hopper adapted to reciprocate in slideable contact with a stencil plate and through the open bottom of which the confection coating may be fed through stencil openings without smearing or spreading over the surface of the stencil plate.

A further object is to provide an improved hopper and stencil plate mechanism by which the confection coating may be confined within the ends of the open bottom walls of the hopper as it moves in slideable contact over the stencil plate.

Still another object of the invention is to provide an improved hopper mechanism for a wafer coating machine which is adapted to be held in a single, scraping, line contact with a stencil plate as it reciprocates thereover.

Another further object is to provide a rockable hopper mechanism for a wafer coating machine which is rockably mounted relative to the stencil screen and which is provided with scraping edges at the bottoms of its opposite side walls adapted to alternately engage the upper surface of the stencil plate, the entire weight of the hopper being borne on alternate strokes on the respective scraping edges and the edges remaining in intimate line bearing contact with the stencil plate.

Other and further objects and advantages of the present invention will become apparent as this description progresses, reference being had to the accompanying drawings, in which:

Figure 1 is a side elevational view of a machine for coating wafers to which one embodiment of the improved hopper and hopper control mechanism comprising my invention has been applied.

Fig. 2 is an enlarged, fragmentary, side elevational view illustrating the hopper and hopper control mechanism;

Fig. 3 is a vertical, transverse, sectional view taken on the line 3—3 of Fig. 2, looking in the direction of the arrows;

Fig. 4 is a fragmentary, longitudinal, vertical sectional view taken on the line 4-4 of Fig. 3, looking in the direction of the arrows and illustrating the operating positions of the hopper and the punch out or stripper fingers;

Fig. 5 is a fragmentary, top plan view of the hopper and the front or feed end of the machine; and

Fig. 6 is a vertical, longitudinal sectional view of the hopper showing its position relative to the 10 die or stencil plate as it slides thereover to apply a confection coating on a wafer therebelow.

By reference to Fig. 1 of the drawings, it will be seen that the wafer coating machine to which the hopper and hopper control mechanism of the present invention has been applied comprises generally a supporting frame structure having vertical, longitudinally extending plates 10 and a plurality of cross pieces or braces, some of which will be referred to specifically hereinafter. As will hereinafter be described in detail, the various operating shafts of the machine are supported between these side plates 10. At the top of the frame structure there is supported an intermittently movable conveyor belt 11 which extends from the front or feed end of the machine (from the left end as viewed in Fig. 1) to the rear or delivery end thereof (the right end thereof). The wafers are fed onto the moving conveyor belt 11 by a feeding mechanism, indicated generally by the numeral 12, and they then pass under the improved hopper and stencil mechanism, indicated generally by the numeral 13, where they are coated with an icing or similar confection material. The belt 11 is stationary during the 15 stencil operation.

After receiving the confection coating, the wafers then pass under a second wafer feeding mechanism, indicated generally by the numeral 14, from which top wafers are positioned down 20 onto the coating. Thus there are formed composite cookies of the sandwich type comprising top and bottom wafers with the confection material therebetween. The completed sandwich 25 cookies thereafter pass on off the machine to a loading area in which they are removed from the conveyor and placed in containers.

The belt 11, as shown best in Fig. 1, is endless in construction, and at its left end it extends 30 around and is supported by a drum 16 and at its right end it extends around a smaller drum or roller (not shown). Intermittent movement of the drum 16 is effected by means of a ratchet wheel 17 loosely mounted on a cross rock shaft 18 and secured to the drum 16, the drum 16 also 35 being supported on the shaft 18 for rotative movement relative thereto. The ratchet wheel 17 is engaged by a pawl 19 pivoted to the upper end of a short arm 20 fixed to the cross shaft 18 and extending upwardly at a forty-five degree angle therefrom. Depending from and fixed to the cross shaft 18 is another short arm 21, the lower end of which is pivotally connected to the upper end of a pitman rod 22. The rod 22 is eccentrically mounted on a continuously rotating shaft 23 so that through the rod 22 and the arm 21, 40 the arm 20 is rocked from left to right causing the pawl 19 to intermittently rotate the drum 16 and advance the belt 11 to the right in a step by step movement.

As shown clearly in Figs. 1, 2 and 3, the shaft 23, which is the main driving shaft of the machine from which movements of the various mechanism to be described hereinafter are effected, extends transversely of the machine, and

it is supported at its ends in bearings secured in the side plates 10 and is supported intermediate its ends by an upstanding column 24 secured on a cross bar 26 of the frame. Rotation of the shaft 23 is effected by a sprocket 27 keyed thereon and engaged by an endless chain 28. The chain 28 extends to the right to the rear of the machine and is operably connected through suitable driving connections to a source of power such as an electric motor (not shown).

The cookie feeding mechanism 12 is also operated off the shaft 23 as seen best in Fig. 1. A horizontal rod 29 has its right end eccentrically secured to the shaft 23 and its forward end adjustably and pivotally connected by a pin and slot connection to the lower end of a rocking lever 30. The lever 30 is pivotally mounted intermediate its ends on a short cross shaft 31 supported in the machine frame and its upper end is pivoted to the rear end of a short link 32 secured to the rear end of a reciprocable slide 33. Above the slide 33 there is supported a wafer magazine 34 comprising a plurality of vertical chutes adapted to receive a plurality of pre-baked wafers in stacked relation which feed downwardly by gravity onto a table 36 over which the slide 33 reciprocates. The magazine 34 is spaced above the table 36 a distance slightly greater than the thickness of the wafer to permit one wafer at a time to drop below each of the chutes. The slide 33 is slightly less in thickness than the thickness of the wafer and its right or rearward edge is adapted to engage the plurality of wafers and to push them off the table 36 onto the belt 11. When the slide 33 is retracted to the left, another group of wafers drop down onto the table 36 and they in turn are also forced onto the belt as the slide is again moved to the right.

As the belt 11 thereafter moves intermittently to the right, the wafers are moved under a flat, horizontal stencil plate 37 (Figs. 2, 4 and 6) having a plurality of transversely aligned openings 38 therethrough and upstanding marginal walls 39, the plate 37 and the walls 39 comprising a stencil box. The stencil box is supported in fixed position in spaced relation from and over the belt 11 on pairs of spaced arms 40 projecting inwardly from pairs of spaced posts secured on the top of each side of the machine frame. An elongated hopper 41 is slidably supported on the stencil plate 37 for reciprocal scraping movement over the top surface thereof and is adapted to be filled with a quantity of confection material of a rather high viscosity. The hopper 41 which is open at both its top and bottom is formed by side walls 42 and vertical end walls 43. The side walls 42 taper downwardly and inwardly toward each other until a point a short distance above the stencil plate, so as to form a throat at which point the walls 42 taper outwardly in the reverse direction to a limited extent to provide a flared bottom.

As the hopper reciprocates it moves from one side of the stencil box to the other passing over the openings 38 on each stroke, the openings conforming to the shape of the wafer but being slightly less than the diameter thereof. When the hopper 41 passes over the openings 38 a quantity of the coating material is forced down within the opening 38 and onto the top surface of the wafer, which is held in raised position up against the under surface of the stencil plate 37 by a mechanism to be described presently. As shown in Fig. 6, the thickness of the stencil

plate 37 determines the thickness of the coating 44 applied to the wafer 46.

The hopper 41 is rockably supported on and relatively to the stencil plate 37, in a manner to be described presently, in order that only one of the side walls 42 thereof will contact the stencil plate 37 during sliding, scraping movement and the other side wall will be slightly raised therefrom. By such a construction the bearing engagement of the hopper 41 will be restricted to a knife edge or line contact and the full combined weight of the hopper 41 and the coating material therein will be applied to the stencil plate 37 only along that single line of contact. This means that only a single lower edge of the hopper 41 will remain in intimate line contact with the stencil plate 37 during sliding movement and the confection material does not have sufficient body to hold the hopper out of such contact. Consequently, as the hopper 41 slides over the plate, it scrapes clean the upper surface and prevents the coating material from working its way out over the stencil plate surface and from forming large masses at the ends of the hopper strokes. The rocking movement of the hopper 41 occurs at the end of each stroke so that the hopper slides first in one direction on one line edge of the bottom of one side wall 42 and then in the other direction on the line edge of the bottom of the opposite side wall 42.

The mechanism for causing reciprocal sliding and rocking movement of the hopper 41, as shown in Figs. 2 to 6 of the drawings, comprises a pair of horizontally disposed bars or slides 47 slidably supported adjacent each end wall 43 of the hopper in channels of horizontal guides 45 secured to the supporting arms 90. The slides 47 are held down within the guide channels by retaining plates 48 secured to the top surfaces of the guides 45. Secured on the upper surface of each of the slides 47 are a pair of spaced blocks 49, the space between these blocks being sufficient to admit a circular bar 50 projecting outwardly from each of the vertical end walls 43 of the hopper 41 below the center line thereof. By engagement of the projecting bars 50 of the hopper with the blocks 49 of the slides 47, sliding movement of the hopper 41 is effected across the stencil plate.

Sliding movement of the slides 47 is achieved by a mechanism now to be described. As shown in Fig. 2, the slides 47 at their right ends and at each side of the machine are pivotally engaged with upstanding short links 51 and also with horizontally extending short links 52, the right end of these links 52 being pivotally secured by pins 52b to the upper end of long rocker arms 53 pivoted at their lower ends to the frame structure on a cross shaft 54 for rocking movement. The links 51 are pivoted intermediate their ends on pins 51a projecting outwardly from upstanding, stationary lugs 47a on the right end of the slide 47 at each side thereof, while the upper ends of links 51 are pivotally connected to the lower ends of links 70 by pins 70a and the lower ends of links 51 are pivotally connected to the left ends of the links 52 by pins 52a. Thus, when the rocker arms 53 are rocked either to the right or to the left, the links 51 will turn about the center pivot pins 51a to effect movement of the links 70 in one direction or the other as will be explained more fully hereinafter. At the same time, movement of the rocker arms 53 will also move the entire slides 47 in one direction or the other, the driving force 75

being transmitted from the rocker arms 53 through the pins 52b, the links 52, the pins 52a, the links 51 and the pins 51a to the slide lugs 47a. The rocker arms 53 intermediate their ends are connected by a cross bar 56 which is received within a slot 57 in the right end of a link 58. The link 58 at its left end is pivotally connected with the right end of a pair of curved spanning links 59, the left end of the links 59 being pivotally connected to the upper ends of a pair of curved hopper cam levers 60. The right ends of the spanning links 59 are also pivotally connected to the upper ends of a pair of curved hopper cam levers 61 and each of the lower ends of the pairs of cam levers 60 and 61 is pivoted to a longitudinally extending brace 62 of the frame structure.

At the pivotal connection between the spanning links 59 and the cam levers 60 there is secured a roller or cam follower 63 and at the connection between the spanning links 59 and the cam lever 61 there is also secured another cam follower 64, these cam followers 63 and 64 being adapted to cooperate with a large cam 66 keyed to a rotatable shaft 67. The shaft 67 is driven by a large gear 68 keyed thereon which is in mesh at all times with a smaller gear 69 keyed to the main driving shaft 23. A sliding clutch member 65 is slidably mounted on the shaft 23 and is secured to the end of shaft 75 to which is secured a clutch lever 75a.

Thus, as the cam 66 is rotated by the shaft 67 the spanning links 59 will be forced to the left or to the right depending upon the position 35 of the cam 66. This causes the link 58 also to move to the left or to the right so as to rock the elongated vertical levers 53 about their pivot 54. As the levers 53 are so rocked, the slides 47 are caused to reciprocate by means of the connecting links 52, the hopper 41 thus being reciprocated back and forth over the stencil plate 37.

As seen best in Fig. 2, the upper end of the short links 51 which project upwardly from the right ends of the slides 47 are pivotally secured at each side of the hopper 41 to angular, forwardly extending links 70, the forward ends of which are pivotally connected to pins 71 (Fig. 3) projecting outwardly from the end walls 43 of the hopper 41 adjacent the upper edge and on the center line thereof. By this construction rocking as well as sliding movement of the hopper is effected. As the blocks 49 push against the hopper bars 50 below the center line of the hopper 41, a force is simultaneously exerted against the upper portion of the hopper 41 in the opposite direction by the links 51 and 70 thus causing the hopper to tilt in the proper direction determined by which end of the stencil plate the hopper happens to be.

This movement of the hopper 41 is clearly illustrated in Figs. 4 and 6 of the drawings. In Fig. 6, the hopper 41 is illustrated in the course of its movement from right to left with the lower edge of the right side wall 42 of the hopper being in line contact with the upper surface of the stencil plate 37 and with the lower edge of the left side wall 42 of the hopper 41 being in raised position. In Fig. 4 the hopper is shown as it appears at each end of its strokes but before it has been rocked for the return stroke. The hopper shown in full lines at the right still has the lower edge of its left side wall 42 in engagement with the upper surface of the stencil plate 37, this line contact having existed all the time the hopper was moving from the left position to the right

position. However, as the slides 47 begin their movement to the left under the driving mechanism above described, the right hand block 49 will exert a pushing force against the hopper pin 50 below the center line of the hopper and at the same time the lever 10 will cause a pulling force to be exerted against the pin 11 of the hopper above the center line in the opposite direction thus causing the hopper to tilt relative to the upper surface of the stencil plate 37 so that the lower edge of the right side wall 42 will now be moved downwardly into scraping, line contact with the stencil plate 37 and the lower edge of the left side wall 42 raised therefrom.

Similarly when the hopper reaches the left hand position as shown in Fig. 4 and the slide begins its movement to the right, the left hand block 49 will exert a pulling force on the hopper pin 50 in the opposite direction and the arm 10 will exert a pushing force on the upper end of the hopper thereby causing tilting thereof in the opposite direction.

By means of this scraping or squeegeeing action of the trailing edge of the hopper, in line contact with the stencil plate 37, the coating material within the hopper is confined between the flared bottoms of the side walls 42 during sliding movement thereof across the stencil plate 37 and also during the time when the hopper is rocked at the ends of its strokes. Because of the line contact between the trailing edge of the hopper and the stencil plate 37 none of the coating material is left behind on the stencil plate during sliding movement but is always forced ahead of the trailing edge. It is to be noted that because the advance edge of the hopper is raised from the stencil plate there is a space through which the coating material might pass were it not for the fact that the movement of the hopper is sufficiently rapid and the coating material is sufficiently plastic to prevent such leakage. The advance raised edge always remains ahead of the coating material which is forced down by a mechanism to be later described against the upper surface of the stencil plate 37 immediately inwardly of the advance edge. Thus when the hopper 41 is rocked and the other edge moves downwardly into contact with the stencil plate 37, no coating material is interposed therebetween. The engagement, therefore, between the hopper edges and the stencil plate is in most instances a clean line contact. However, in the event the viscosity of the coating material is of a lower degree so that it is somewhat more flowable to permit slight leakage ahead of the raised side wall of the hopper during sliding movement, nevertheless because of the line contact the edge of the hopper upon rocking movement will cut down through such coating material into intimate engagement with the stencil plate and wipe the plate clean on its return movement. It is thus apparent that by this novel form of hopper and hopper control mechanism the stencil box is kept relatively free of coating material and no large masses thereof are permitted to form at each end of the hopper stroke. Consequently, most or all of the coating material is forced down through the stencil openings 38 onto the wafers therebelow and the services of an operator in seeing that the stencil box is kept clean are dispensed with.

In order to raise the wafers 46 up against the under surface of the stencil plate 37 there is provided a channel-shaped member 72 which extends transversely of the machine beneath the

belt 11, the upper edges of the channel member 72 being adapted to engage the under surface of the belt 11 at points spaced from either side of the wafer so as not to damage the same. The channel-shaped member 72, as shown particularly in Fig. 3 of the drawings, is secured at each of its ends to the upper ends of reciprocal lifting rods 73 which are slidably received through a vertical opening 74 in inwardly projecting frame members 76 at each side of the machine. The lower ends of the lift rods 73 are bifurcated to receive a cam roller 77 which is in constant engagement with a small cam 78 keyed to the rotating shaft 67. The cam surface of the cam 78 is of such configuration that the lift rods 73 are caused to be moved up and down at the proper intervals so that the wafers 46 will be raised into position under the stencil plate 37 prior to the time the hopper 41 slides over the stencil plate to deposit a coating 44 simultaneously on each of the wafers.

After the coating 44 has been applied to the upper surfaces of the wafers, the coated wafers tend to adhere to the under surface of the stencil plate 37 due to the tackiness of the coating material. Provision is therefore made for releasing the coated wafers so they may be restored to position on the belt 11 as it is lowered for further intermittent movement. This releasing or stripping means comprises two sets of stripping or punch-out fingers 79 arranged in aligned groups on each side of the hopper 41 and adapted to be projected downwardly through the hopper openings 38 so as to push the coated wafers down away from the stencil plate 37. The sets of stripping fingers 79 are alternately operable after the hopper 41 has passed over the stencil plate openings 38 and is approaching the end of its stroke.

Each of the sets of stripping fingers 79 depend from a transversely extending bar 80 having upwardly turned ends 81 at each side thereof secured to vertically slidable blocks 82 at each side of the hopper. The transversely opposed blocks 82 at each side of the machine are secured together by cross bars or braces 83 so as to operate in their vertical movements as a unit. Each of the blocks 82 is provided with a central opening through which extend vertically directed rods 84 secured to the upper surface of the slides 47. Projecting outwardly from each of the blocks 82 on each side of the machine is a roller 86 which is adapted to engage the upper surfaces of two inclined tracks 87 and 88 on each side of the machine secured on the guide members 45.

The stripper bars 80 are, therefore, adapted to be raised and lowered at appropriate times as the hopper moves from one side of the stencil plate to the other. Referring to Figs. 2 and 4 of the drawing, it will be seen that when the hopper 41 is in its right hand position on the stencil plate 37, the right hand stripper mechanism and its roller 86 is adjacent the upper right end of the trackway 88. As the hopper 41 moves to the left, the stripping mechanism is also carried to the left on the slides 47, the roller 86 rolling down the inclined track 88 to the lower end thereof. When this point is reached, the hopper has entirely passed over the stencil plate openings 38 and the coated wafer is ready to be released. Thus at this point the stripping fingers 79 are permitted to drop down through the stencil plate openings 38 with a sharp sudden movement so as to punch out the adhering wafers without separating the coating therefrom. This sudden dropping movement of the stripping fin-

gers 79 is caused by the sudden dropping off of the rollers 86 from the trackway 88, the trackways 87 and 88 being spaced apart at their lower adjacent edges to permit the roller 86 to drop downwardly therebetween.

Similarly, when the hopper 41 is in its left hand position as shown in Fig. 4 by the broken lines, the stripper mechanism on the left side thereof is at the upper end of the inclined trackway 87, and as the hopper 41 is moved to the right, the stripping mechanism is gradually lowered until the roller 86 thereof suddenly drops off the lower end of the trackway 87, the coated wafers which were coated on the movement of the hopper from left to right thus being punched downwardly in similar manner.

Before the hopper 41 may commence its return stroke, it is necessary to elevate the stripping mechanism and the stripping fingers 79 from the stencil plate openings 38 and this is accomplished by vertical lift rods 89 on each side of the machine which are adapted to engage the rollers 86 of each of the stripping mechanisms. The lift rods 89, as shown in Figs. 2 and 3 of the drawings, are slidably received within the inwardly projecting frame members 76 and 90, the lower end of the lift rods 89 being bifurcated to support cam rollers 91. The cam rollers 91 are adapted to constantly engage a cam 92 also keyed on the rotating shaft 67. The configuration of the cam 92 is such that the lift rods 89 are elevated into engagement with the rollers 86 so as to lift the rollers above the lower edges of either the trackways 87 or 88 just before the hopper 41 commences its return movement. The lift rods 89 serve to elevate at the proper times both the right and left stripper mechanisms.

In order that the coating material may be under constant feeding pressure within the hopper 41 as the hopper slides over the stencil plate openings 38, there is provided a vertically reciprocable feeding member 93, shown particularly in Figs. 2, 3 and 5 of the drawings. This pressure member comprises an enlarged cylindrical bar 94 extending horizontally within the hopper between the side walls 43 thereof for movement downwardly from approximately the center line of the hopper. This enlarged pressure bar 94 is supported by spaced vertical bars 96 whose upper ends are in turn secured to a horizontal cross bar 97, the respective ends of which project beyond the end walls 43 of the hopper. These projecting ends of the cross bar 97 are provided with depending arms 98 and the lower ends of these depending arms are provided with oppositely directed slide bars 99 so as to form an inverted sloping T. The slide bars 99 are adapted to alternately engage the upper surfaces of the tracks 87 and 88 and they are of sufficient length to bridge the gap between the tracks 87 and 88. Slide bars 99 are angularly disposed with respect to the depending arms 98 so as to be in planes parallel to the tracks 87 and 88, respectively, thus facilitating sliding movement.

The vertical bars 96 of the pressure member 93 adjacent the end walls 43 of the hopper are slidably received in vertical channels 85 (Figs. 3 and 5) cut in the inner surface of the end walls 43 of the hopper so that the vertical movement of the pressure member 93 is guided thereby. Thus when the hopper is moved from one end of the stencil plate 37 toward the openings 38, the pressure bar 94 moves downwardly within the hopper exerting a pressure on the coating material below it, this lowering of the pressure bar 94

being permitted as the slide bars 99 slide downwardly on one of the inclined tracks 87 or 88, and the point of greatest pressure being directly over the center of the openings 38 in the stencil plate 37. As the hopper continues on toward the end of its stroke, the pressure bar is then raised as the bar 99 slides up the opposite track.

After the wafers 46 have been coated and released from the stencil plate 37 by the stripping mechanism, they continue intermittently onwardly on the belt 11 until they pass under another wafer magazine 100 also comprising a plurality of vertical chutes. These chutes are also filled with wafers which are fed onto the coating material 44 of the previously coated wafers by means of a slide 101 operably connected with the motor 12, thereby forming a sandwich cookie.

Although there has been described above and illustrated in the drawing a preferred embodiment of a hopper and hopper control mechanism for a wafer coating machine, it is to be understood that changes and modifications may be made in the structural details and mode of operation thereof without departing from the spirit and scope of the appended claims.

I claim:

1. In a machine for coating cakes having a stencil plate with an opening therein and means for supporting a cake adjacent said opening, the combination of a hopper having opposed side walls and a bottom opening between said side walls and being adapted for reciprocal sliding movement across said stencil plate in engagement therewith and for tilting movement relative thereto, supporting mechanism for rockably and slidably supporting said hopper with its bottom opening and the lower ends of the side walls adjacent said stencil plate for tilting movement and sliding movement relative to said plate, the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate, rocking means operably connected with said hopper for tilting the hopper in alternate directions, and actuating means for slidably reciprocating said hopper in tilted position across said plate.

2. In a machine for coating cakes having a stencil plate with an opening therein and means for supporting a cake adjacent said opening, the combination of a hopper having opposed side walls and a bottom opening between said side walls and being adapted for reciprocal sliding movement across said stencil plate in engagement therewith and for tilting movement relative thereto, supporting mechanism for rockably and slidably supporting said hopper with its bottom opening and the lower ends of the side walls adjacent said stencil plate for tilting movement and sliding movement relative to said plate, the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate, and hopper tilting and sliding means for tilting the hopper in alternate directions at the ends of its respective strokes

11

and for reciprocating said hopper in tilted position across said stencil plate.

3. In a machine for coating cakes having a stencil plate with an opening therein and means for supporting a cake adjacent said opening, the combination of a hopper having opposed side walls and a bottom opening between said side walls and being adapted for reciprocal sliding movement across said stencil plate in engagement therewith and for tilting movement relative thereto, supporting mechanism for rockably and slidably supporting said hopper with its bottom opening and the lower ends of the side walls adjacent said stencil plate for tilting movement and sliding movement relative to said plate, the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate, and hopper tilting and sliding means for tilting the hopper in alternate directions at the ends of its respective strokes and for reciprocating said hopper in tilted position across said stencil plate, said means comprising a member engaging said hopper at the lower portion thereof and exerting a force thereagainst in the direction of movement of said hopper and a member engaging the hopper at its upper portion and adapted to effect tilting movement thereof in the opposite direction.

4. In a machine for coating cakes having a stencil plate with an opening therein and means for supporting a cake adjacent said opening, the combination of a hopper having opposed side walls and a bottom opening between said side walls and being adapted for reciprocal sliding movement across said stencil plate in engagement therewith and for tilting movement relative thereto, supporting mechanism for rockably and slidably supporting said hopper with its bottom opening and the lower ends of the side walls adjacent said stencil plate for tilting movement and sliding movement relative to said plate, the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate, actuating means mounted adjacent each end of the hopper at the lower portion thereof for reciprocal movement relative to the stencil plate and for effecting reciprocal movement of the hopper and including a pair of spaced members, a stud projecting from the lower portion of each end of the hopper into engagement with and between said members, and tilting means also carried by the actuating means and comprising an arm pivotally engaging the hopper at the upper portion thereof for tilting the hopper in direction opposite to that of its bodily movement.

5. In a machine for coating cakes having a stencil plate with an opening therein and means for supporting a cake adjacent said opening, the

12

combination of a hopper having opposed side walls and a bottom opening between said side walls being adapted for reciprocal sliding movement across the plate in engagement therewith and for rocking movement relative thereto, reciprocal supporting mechanism for rockably and slidably supporting said hopper with its bottom opening and lower edges of the side walls adjacent said stencil plate for rocking movement and sliding movement relative to said plate and including reciprocal actuating means mounted for reciprocal movement relative to said stencil plate and interconnecting means between the actuating means and the hopper for rockably supporting said hopper on the actuating means and for effecting sliding movement of the hopper upon movement of the actuating means, and rocking means operably engaged with the hopper for rocking the same in alternate directions on said actuating means, the lower edge of only one side wall being adapted to be in scraping contact with said plate when the hopper is tilted in one direction and moved across said plate and the lower edge of only the other side wall being adapted to be in scraping contact with the plate when the hopper is tilted in the opposite direction and moved in the return direction across the plate.

6. In a machine for coating cakes having a stencil plate with an opening therein and means for supporting a cake adjacent said opening, the combination of a hopper having opposed side walls and a bottom opening between said side walls and being adapted for reciprocal sliding movement across the stencil plate in engagement therewith and for tilting movement relative thereto, slideable supporting mechanism for rockably and slidably supporting said hopper with its bottom opening and lower ends of the side walls adjacent said stencil plate for tilting and sliding movement relative to the stencil plate, and interconnecting means between the slide means and the hopper below the center of gravity of the hopper for tiltably supporting said hopper on the slide means and for effecting sliding movement of the hopper upon movement of the slide means, actuating mechanism for effecting reciprocal movement of the slide means, and rocking means operably engaged with the upper portion of the hopper above the center of gravity for tilting the hopper in alternate directions, the lower edge of only one side wall being adapted to be in scraping contact with said plate when the hopper is tilted in one direction and moved across said plate and the lower edge of only the other side wall being adapted to be in scraping contact with the plate when the hopper is tilted in the opposite direction and moved in the return direction across the plate.
